CLAIM

We claim the ornamental design of a shoe, as shown and described.

DESCRIPTION

FIG. 1 is a side perspective view of a shoe;

FIG. 2 is a second side perspective view thereof;

FIG. 3 is a front view thereof;

FIG. 4 is a rear view thereof;

FIG. 5 is a side view thereof;

FIG. 6 is a second side view thereof;

FIG. 7 is a top view thereof; and,

FIG. 8 is a bottom view thereof.

The broken lines shown in the drawings represent portions of the shoe that form no part of the claimed design.
